[57] CLAIM

The ornamental design for a collapsible mobile work platform having telescopic legs, as shown and described.

DESCRIPTION

FIG. 1 is a side elevational view of a collapsible mobile work platform having telescopic legs showing my new design;

FIG. 2 is a left end elevational view thereof;

FIG. 3 is a top plan view thereof;

FIG. 4 is a perspective view thereof on a reduced scale;

FIG. 5 is a perspective view thereof on a reduced scale in collapsed condition;

FIG. 6 is a greatly enlarged perspective view of one of the telescopic leg tubes of the work platform;

FIG. 7 is a perspective view of FIG. 6 turned clockwise approximately 45°; and

FIG. 8 is a top plan view of FIG. 6.

FIG. 1***FIG. 2******FIG. 3***FIG. 5

FIG. 4

*FIG. 6**FIG. 7**FIG. 8*
